Bird West

INVENTOR.

UNITED STATES PATENT OFFICE.

BINA M. WEST, OF PORT HURON, MICHIGAN.

DESIGN FOR A BROOCH.

59,799.

Specification for Design.

Patented Nov. 22, 1921.

Application filed March 28, 1921. Serial No. 456,497. Term of patent 7 years.

To all whom it may concern:

Be it known that I, BINA M. WEST, a citizen of the United States, residing at Port Huron, in the county of St. Clair and State of Michigan, have invented a new, original, and ornamental Design for a Brooch, of which the following is a specification, reference being had to the accompanying drawing, forming part thereof.

The figure is a plan view of a brooch, showing my new design.

I claim:

The ornamental design for a brooch, as shown.

BINA M. WEST.
